POCKET CLEANER

Otto O. Fickeissen, St. Louis, Mo., assignor to
Atlas Linen & Towel Service Company, St.
Louis, Mo., a corporation of Missouri

Application January 22, 1935, Serial No. 2,949

1 Claim. (Cl. 15—7)

This invention pertains to new and useful improvements in cleaners for apparel and more particularly to an apparatus especially adapted for treating garment pockets.

5 The principal object of the present invention is to provide a pocket cleaner including a rigid nozzle which can be readily inserted into a pocket.

10 Another important object of the present invention is to provide a pocket cleaner including a nozzle and suction means therefor, with a movable brush at the inlet of the nozzle for loosening foreign matter in the pocket being cleaned.

15 Other important objects and advantages of the invention will become apparent to the reader of the following specification.

In the drawing:

Figure 1 represents a perspective view of the apparatus.

20 Figure 2 represents an enlarged fragmentary vertical sectional view through the apparatus.

Figure 3 represents an enlarged fragmentary detailed sectional view taken substantially on line 3—3 of Figure 2.

25 Referring to the drawing wherein like numerals designate like parts, it can be seen in Figure 1 that numeral 5 denotes a work bench upon which the novel apparatus generally referred to by numeral 6 is secured.

30 The apparatus can be secured upon the table as shown in Figure 1 or with the major portion thereof secured under the table as shown in Figure 2. Referring to Figure 1, it can be seen that numeral 7 denotes a housing above which rises the elongated conduit 8 terminating in the nozzle 9, the upper end of which is rounded off and provided with the slot 10 therein through which the bristles 11 of the brush 12 protrude as the brush is rotated. The brush 12 (see Figure 2) 35 is provided with a pulley 13, the brush being rotatably mounted on the member 14.

40 The housing 7 has the motor 15 secured thereto from which the shaft 16 extends to project into the lower end portion of the conduit 8. On the shaft 16 is the suction fan 17 along with

the small pulley 18. A belt 19 is trained over the pulleys 13 and 18 and in this manner the motor 15 not only drives the suction fan 17 but also the brush 12.

45 As is clearly shown in Figure 1, the housing 7 is provided with the upstanding plate 20 having opening 21 therein through which securing elements can be disposed for securing the plate to the edge portion of the work bench 5 in the manner substantially shown in Figure 2.

10 Furthermore the conduit 8 is in sections, the same being divided longitudinally and provided with suitable means 22 whereby the sections of the conduit can be detachably connected.

15 Numeral 23 represents the suction bag while 24 represents the wires extending from the motor 15 to the plug 25 and also to the floor switch 26.

20 Obviously with the conduit 8 extending upwardly above the top of the table 5, a garment can be disposed over the same so that the pockets of the garment can receive the nozzle 9 and when the motor 15 is energized, the brush 12 will serve to loosen up any hairs or foreign matter in the pockets which will be sucked into the bag 25 23 by the motor 15 and fan 17.

25 While the foregoing specification sets forth the invention in specific terms, it is to be understood that numerous changes in the shape, size, materials may be resorted to without departing 30 from the spirit or scope of the invention as claimed hereinafter.

35 What is claimed as new is:

A pocket cleaner comprising a housing, a suction fan in the housing, a shaft for supporting the suction fan, a pulley on the shaft, an elongated pocket insertable nozzle extending from the housing, and having a narrow slot in the outer end thereof, a thin rotary brush in the outer end of the nozzle with its peripheral portion 40 protruding through said slot, a pulley on the brush maintaining the brush toward one side of the said slot to define a suction passageway, and drive means between the said pulleys.

45 OTTO O. FICKEISSEN.
